UNITED STATES PATENT OFFICE.

SAMUEL J. WOOD, OF LOS ANGELES, CALIFORNIA.

DESIGN FOR A BOTTLE.

58,174.

Specification for Design. Patented June 14, 1921.

Application filed October 29, 1920. Serial No. 420,576. Term of patent 7 years.

To all whom it may concern:

Be it known that I, SAMUEL J. WOOD, a citizen of the United States, residing at Los Angeles, in the county of Los Angeles and State of California, have invented a new, original, and ornamental Design for a Bottle, of which the following is a specification, reference being had to the accompanying drawing, forming a part thereof, in which bands with arrowheads appear at top and bottom of the bottle body.

The figure is a front view of the bottle showing the design.

I claim:

The ornamental design for a bottle, substantially as shown.

Signed at Los Angeles, in the county of Los Angeles, and State of California, this 23rd day of October, 1920.

SAMUEL J. WOOD.

Witness:

JAMES R. TOWNSEND.
